PROCESS OF MAKING ALLO-OCIMENE

Robert C. Palmer and Carlisle H. Bibb, Pensacola, Fla., assignors to Newport Industries, Inc., Pensacola, Fla., a corporation of Delaware

No Drawing. Application December 23, 1940,
Serial No. 371,410

8 Claims. (Cl. 260—677)

This invention relates to a process for making allo-ocimene by thermal decomposition of alpha-pinene. More particularly, the invention relates to a rupturing of carbon to carbon linkages in alpha-pinene under regulated, favorable thermal conditions with the formation of allo-ocimene.

The reaction, in accordance with which carbon to carbon linkages in alpha-pinene are ruptured to form allo-ocimene, may be graphically illustrated as follows:

The above graphic illustrations indicate that a rupture occurs in both the 4 and 6 carbon rings in order to form allo-ocimene. However, where the rupture occurs only in the 4 carbon ring, the resulting product is dipentene. Actually, both allo-ocimene and dipentene are obtained by the process of our invention.

Although alpha-pinene is apparently stable at its boiling point of 156° C., we have found that when alpha-pinene in the liquid phase is heated to temperatures definitely above 156° C., the alpha-pinene undergoes a structural change into allo-ocimene and dipentene. Allo-ocimene, however, being a hydrocarbon containing 3 double bonds which are arranged in double conjugation, is very reactive, and it may be lost unless special precautions are taken for its preservation. For instance, when alpha-pinene alone is heated for 2 hours in the liquid phase at 250° C., it is converted into about 70% of monocyclic terpene hydrocarbons, largely dipentene, and 20% of high boiling polymers, with about 6% of the alpha-pinene remaining unreacted. The high boiling polymers are formed principally from a polymerization of allo-ocimene.

We have now discovered that when the reaction is carried out by heating the alpha-pinene dissolved in a relatively high boiling diluent, relatively large amounts of allo-ocimene can be removed from the solution by steam distillation, while the amount of high boiling polymers is reduced from 20% to around 1 or 2%. The steam distillate can itself be fractionally distilled into a

fraction consisting largely of dipentene and another fraction consisting largely of allo-ocimene.

It is thus an important object of this invention to provide a process for making allo-ocimene from alpha-pinene by thermal transformation of the alpha-pinene in liquid phase at a temperature above the normal boiling point of alpha-pinene.

It is a further important object of this invention to provide a process for making allo-ocimene by the thermal conversion of alpha-pinene while avoiding the formation of substantial amounts of high boiling polymers.

It is a further important object of this invention to provide a process for the thermal isomerization of alpha-pinene in liquid phase into allo-ocimene and dipentene, from the mixture of which allo-ocimene can be recovered by fractional distillation.

Other and further important objects of this invention will become apparent from the following description and appended claims.

The term "dipentene" as used in this specification refers to the chemical substance known as dl-limonene, namely a mixture of d- and l-limonene. The word "dipentene" is used so loosely in the literature for describing various mixtures of monocyclic hydrocarbons which consist of the terpinenes, terpinolene and sometimes little or no actual dipentene, that a chemical test must be made to determine whether what the literature has designated as "dipentene" is actually dipentene.

In the present process, dipentene, or dl-limonene, constitutes the major portion of the hydrocarbons formed other than allo-ocimene. This is unusual because most processes for isomerizing alpha-pinene to monocyclic hydrocarbons yield the terpinenes and terpinolene as the major products.

The following example will serve to illustrate a preferred embodiment of our invention, but it will be understood that our invention is not limited to the specific details of the example:

Example

110 gals. of alpha-pinene were dissolved in 720 gals. of a high boiling mineral oil, such as a mineral oil having a boiling point of around 300° C., and heated to the boiling temperature of the solution for 6 hours. The solution started to boil at 225° and heating was stopped when the temperature had reached 240° C., which temperature was reached at the end of the 6 hour period. The mixture was then steam distilled

at 150° C. and 112.0 gals. of oil collected as distillate. The oil distillate had a specific gravity at 15/4° C. of 0.8444 and a refractive index at 20° C. of 1.4855.

The alpha-pinene used as the starting material was prepared by the fractional distillation of wood turpentine and, when tested, gave a specific gravity at 15/4° C. of 0.8614, with a refractive index at 20° C. of 1.4660.

The 112 gals. of oil collected as distillate in the steam distillation step were then fractionally distilled at 15 mm. (absolute pressure of mercury) using an efficient fractionating column. The results obtained are recorded in the following table:

Product	Volume	Sp. gr. 15/4° C.	R. I. 20
	Gal.		
Unreacted alpha-pinene	27.1	0.8594	1.4688
1st intermediates	7.4	0.8540	1.4707
Dipentene	48.0	0.8446	1.4731
2nd intermediates	3.0	0.8211	1.5221
Allo-ocimene	22.0	0.8121	1.5427
Residue	4.0		

The first intermediate fraction was redistilled into alpha-pinene and dipentene, while the second intermediate fraction was redistilled into dipentene and allo-ocimene. A substantial part of the residue consisted of mineral oil which came over during the steam distillation.

Various changes can be made in the process of the foregoing example without greatly interfering with the results obtained. The time of the reaction can be lessened or prolonged. The ratio of alpha-pinene to the high boiling solvents is not critical, but if a larger proportion of alpha-pinene is used, the temperature at which the solution will boil decreases and the reaction requires more time within which to effect the same amount of chemical change. However, under such circumstances pressures above atmospheric may be used to bring the temperature within the desired range. While mineral oil is given in the example, a large variety of relatively high boiling solvents can be employed, provided that they are inert under the conditions obtaining in carrying out the process. Waxes, ethers, esters and fats, if they meet the requirements as to boiling point and inertness, can be used in place of mineral oils.

The thermal isomerization of alpha-pinene may be carried out within a rather wide temperature range. At a temperature of about 160° C., the rate of reaction is very slow, while at a 180° C. the reaction proceeds at a fair rate. At a temperature of 220° C., the rate of reaction is fairly high, and at 260° C., it may be considered as a relatively fast, with the rate increasing still further as the temperature advances. While the maximum temperature is difficult to define because of practical difficulties in the manipulation of the apparatus and products at high temperatures, it may be placed at around 400° C. on the basis of various considerations. For the purpose of practical operation, the temperature of the reaction should be kept between 180 and 280° C., with the most preferred range at between 225 and 250° C.

While we have designated alpha-pinene as the starting material, it is practical to use a mixture of alpha-pinene and beta-pinene, since beta-pinene tends to change over to alpha-pinene in the process and hence will be converted into dipentene and allo-ocimene in the manner de-

scribed. When using beta-pinene alone, the reaction was found to be much slower.

Thus, where the term "alpha-pinene" is used in the claims, it will be understood that the alpha-pinene may either be the starting material or it may be produced from the starting material during the carrying out of the process defined by the claims. For instance, turpentine is an excellent raw material for use in our process, since it contains pinene. When turpentine is subjected to the process herein described, the pinenes contained therein are converted into allo-ocimene and dipentene. Consequently, any alpha-pinene producing material, or any material containing alpha-pinene, or pure alpha-pinene can be used as a starting material for our process.

It will, of course, be understood that various details of the process may be varied through a wide range without departing from the principles of this invention and it is, therefore, not the purpose to limit the patent granted hereon otherwise than necessitated by the scope of the appended claims.

We claim as our invention:

1. A process of making allo-ocimene, which comprises heating dilute alpha-pinene in liquid phase at a temperature above its normal boiling point until a substantial conversion of said alpha-pinene into allo-ocimene has taken place and recovering allo-ocimene.

2. A process of making allo-ocimene, which comprises heating alpha-pinene in a high boiling solvent therefor in the liquid phase to a temperature of between 160 and 400° C. to convert said alpha-pinene into allo-ocimene and dipentene and recovering the allo-ocimene.

3. A process of making allo-ocimene, which comprises heating alpha-pinene in a high boiling solvent therefor in the liquid phase to a temperature of between 180 and 280° C. to convert said alpha-pinene into allo-ocimene and dipentene and recovering the allo-ocimene.

4. A process of making allo-ocimene, which comprises heating alpha-pinene in a high boiling solvent therefor in the liquid phase to a temperature of between 225 and 250° C. to convert said alpha-pinene into allo-ocimene and dipentene and recovering the allo-ocimene.

5. A process of making allo-ocimene, which comprises heating alpha-pinene in a high boiling solvent therefor in the liquid phase to a temperature of between 225 and 250° C. to convert said alpha-pinene into allo-ocimene and dipentene, steam distilling the allo-ocimene and dipentene from the solvent and separating and recovering the allo-ocimene apart from the dipentene by fractional distillation.

6. A process of making allo-ocimene from alpha-pinene, which comprises dissolving alpha-pinene in a relatively high boiling solvent therefor, heating the resulting solution in the liquid phase under such conditions of temperature and pressure as to cause said alpha-pinene to thermally decompose into allo-ocimene and dipentene, and recovering the allo-ocimene so formed.

7. A process of making allo-ocimene from alpha-pinene, which comprises dissolving alpha-pinene in a relatively high boiling mineral oil to serve as a solvent therefor, heating the resulting solution in the liquid phase under such conditions of temperature and pressure as to cause said alpha-pinene to thermally decompose into allo-ocimene and dipentene, distilling said

allo-ocimene and dipentene from said mineral oil, and recovering the allo-ocimene apart from the dipentene by fractional distillation.

8. A process of making allo-ocimene which comprises heating a liquid containing alpha-pinene at a temperature between 160° and 400° C. while maintaining the alpha-pinene in liquid

phase until a substantial proportion of said alpha-pinene has been converted into allo-ocimene and dipentene, and recovering the allo-ocimene.
